UNITED STATES PATENT OFFICE.

EDWARD FISH, OF NEW YORK, N. Y., ASSIGNOR TO F. L. SMITH MACHINE COMPANY,
INCORPORATED, OF NEW YORK, N. Y., A CORPORATION OF NEW YORK.

FEEDING DEVICE.

1,404,195.

Specification of Letters Patent. Patented Jan. 24, 1922.

Application filed December 21, 1920. Serial No. 432,185.

To all whom it may concern:

Be it known that I, EDWARD FISH, a citizen of the United States, and a resident of New York, borough of Manhattan, in the county of New York and State of New York, have invented certain new and useful Improvements in Feeding Devices, of which the following is a specification.

This invention relates to feeding devices for sheet blanks and particularly to means therein for directing the blanks while being fed. It has for its object to provide a device of the class specified, simple in construction, efficient in operation and which tends to maintain the blank in its previous direction of travel.

With these ends in view and others which will appear hereinafter my improvements comprise features illustrated in the drawing accompanying this specification, wherein:

Figure 1 is a plan view of my device applied, for purposes of illustration, to a machine for making envelopes. Fig. 2 is a side elevation corresponding with the showing of Fig. 1 and looking in the direction of arrow B in said figure. Fig. 3 is a fragmentary view of a portion of what is shown in Fig. 1 but with the parts in different relative positions. Fig. 4 is a fragmentary elevation of a detail of the device. All of the figures are to one scale.

In such machines as are commonly employed for making envelopes from blanks of irregular outline, such as shown at 2 in Fig. 1, the blanks are stacked as at 3, and said blanks are lifted one at a time to the position of blank 2, Fig. 2, by some known means such as gummed pickers, not shown. From there the blank is advanced in the direction of arrow A, Figs. 1 and 2, to the folding box 4 through which it is pushed downwardly by the usual plunger, not shown. In advancing the blank from its position 2 to the folding box, the tendency of the gum 5 on the bottom flap of the envelope combined with the impact against the air is such as often to cause the leading end of the blank to bend downwardly, resulting in the collision of that leading end with the edge 50 of the table or other intervening parts of the machine, to the displacement or destruction of the blank. Various devices have been proposed to remedy this difficulty. The most efficient thereof with which I am acquainted, while successful in projecting a

table under the leading end of the blank prior to its advancement, tends to skew the blank out of its rectilinear travel, thereby delivering the blank at the folding box in skewed position, resulting in a defectively folded envelope.

By my improvements these objectionable features are obviated, as will appear in the following detailed description. Transfer table 6 lies in a plane slightly above that of the top of bed plate 7 and said plate is cut away at 8 to receive the bent down delivery end of said table. Said plate is also cut away at 9 to receive stem 10 of table 6. Said stem terminates downwardly in pivot 11, Fig. 4, which turns in the upper and inner arm of lever 12. Said lever is pivotally mounted at 13 in bed 14. Lever 12 may be oscillated from cam 15 through roll 16 on rock-arm 17, the upper end of which is connected with the outer end, 12^a, of lever 12 by link 18. Roll 16 is urged to engagement with cam 15 by pull spring 19. For maintaining table 6 in parallelism of movement from the position of Fig. 1 to that of Fig. 3, stem 10 is provided with arm 20 fixed thereto, and fixed to post 13 is arm 21 of equal length and extending in the same direction. Said arms 20 and 21 are connected by link 22. By this means table 6, as it moves from the position of Fig. 1 to below the blank, as in Fig. 3, maintains its leading end 6^a normal to the path of the envelope blank to the folding box. After table 6 reaches the position of Fig. 3 the envelope blank is advanced in the direction of its arrow A, thereover, by means not shown but well known in the art. Coincidentally, said table is returned to its position of Fig. 1, preferably before the leading end of the blank passes entirely over said table, thereby bridging gap 8 in bed plate 7 and preventing the leading end of the blank from hooking into said gap. It will be observed that during the movement of said table 6 from the position of Fig. 3 back to that of Fig. 1, the leading end of blank 2 will lie thereon and that any movement of said table in a direction other than that in which it is desired to advance the blank will tend to cause that blank to deviate from that desired direction of travel. For instance, if said table was rigidly secured to lever 12, said table would travel concentrically only and would tend to lead the blank with it, away from

its desired path; but as said table is caused by my improved mechanism to travel in a substantially rectilinear path in the desired direction of travel of blank 2, the tendency 5 of said table is to assist said blank to maintain its correct direction of travel.

I claim:

1. In a blank feeding mechanism the combination of a movable transfer table adapted 10 to support the leading end of the blank, and means for moving said table in an arcuate path in a plane parallel to that of the blank and in parallelism laterally with the path of said blank.
- 15 2. In a blank feeding mechanism the combination of a lever mounted for oscillation in a plane parallel to that of the blank, a

transfer table pivotally mounted on the free end of said lever, and means coacting with 20 said lever for moving said table in an arcuate path in a plane parallel to that of the blank and in parallelism laterally with the path of said blank.

3. In blank feeding means the combination of an oscillating lever, a transfer table 25 pivotally attached to the free end of said lever, and a link, one end of which is pivotally connected to said table at a point other than where said table is connected to said lever and the other end of which is pivotally connected to a fixed part.

In witness whereof, I hereby affix my signature this 17 day of December, 1920.

EDWARD FISH.
